UNITED STATES PATENT OFFICE.

ELI SMITH AND JAMES DUCKWORTH, OF SPRINGFIELD, MASSACHUSETTS.

COMBINATION-TOOL.

SPECIFICATION forming part of Letters Patent No. 268,560, dated December 5, 1882.

Application filed April 10, 1882. (No model.)

To all whom it may concern:

Be it known that we, ELI SMITH and JAMES DUCKWORTH, citizens of the United States, residing at Springfield, in the county of Hampden and State of Massachusetts, have invented new and useful Improvements in Combination-Tools, of which the following is a specification.

This device consists of an adjustable bevel and miter, and also forms a tool having stops to the blade at right angles and at forty-five degrees to the straight edge of the stock, the object of our invention being to provide an improved tool of this class having a fixed stop in its stock, whereby the blade is brought to a position at right angles to the stock, and having a movable stop on the latter, adapted to be swung across the blade-channel therein, in order to stop the blade at an angle of forty-five degrees to said stock, and to be turned back to leave said channel open on one side, so that the blade may be received in the stock in a line therewith, and to provide easily-operated and efficient clamping devices to secure said blade in any desired position.

In the drawings, Figure I is a view of the complete device in perspective. Fig. II is a sectional view; Fig. III, a side view, and Fig. IV a detail view.

The stock D is formed of two sections, held in immediate contact at the rear end of the tool by the screws d d, and at a sufficient interval apart at the front end of the tool to admit of the movement of the blade between the sections and in the channel b by the screw-stud H. The stud H, having its head countersunk in one section of the stock and having its end screwed into the other section, passes intermediately through the slot g of the blade B, and so forms a pivot-stud for the blade.

Loose upon the pivot-stud H, and arranged to have one side bear against a corresponding side of the blade, is a washer, C, and adapted to come against the opposite side of the washer C from that in contact with the blade, is the conical head of a screw-stem, I.

The operation of the mechanism is as follows: By the advancement of the cone under the loose washer bearing against the loose blade, the washer is forced upon the stud, rig-

idly uniting the sections of the stock, to clamp the blade to one section.

In detail the cone-screw I has its nut, as shown in Fig. II, in section, and has its point aligned to pass over the corner of the washer, while its stem is prolonged to extend to the outside of the rear of the tool, where it is provided with the convenient operating-handle m.

The pivot-stud H is provided with a transverse hole, h, to admit of the movement of the point of the cone past the rim of the washer, and in practice we form this hole of sufficient size to permit a rotary play of the stud in adjustment, while still leaving interval for receiving the point of the screw I.

The washer C is allowed movement from the blade when released by the screw I by a countersink in the section from which it moves, as shown in Fig. II.

It will be seen that in this mechanism, by a slight movement of stud H, the other parts can be so adjusted as to cause the slightest movement of screw-stem I to cause the blade to be clamped, and that by the movement of said stud the wear of the parts forming the clamp can be easily taken up.

In order to permit the tool to be quickly and with certainty converted into a try-square, the stop W is arranged transversely across the slit b from section to section, and, being permanently secured to one, is received in a dovetail in the other, by means of which the sections may move in receiving adjustment through the stud H. While the blade is thus stopped on one side of the stock it is free to be moved to any angle upon the other, and to stop it at the frequently-required angle of forty-five degrees a movable stop, V, is formed, as shown in Fig. III, by a hinged piece recessed in the stock to preserve the straight edge, and capable of being easily moved to obstruct the blade or give it free play.

Now, having described our invention, what we claim is—

1. In combination, the stock D, having the channel b between its sides, the blade B, having the slot g therein, the stud H, rigidly fixed in said stock and passing through said slot in blade B, the fixed stop W, set across said channel b on one edge of said stock, the washer

c, loose on stud *H*, and the pointed screw-stem *I*, substantially as set forth.

2. In combination, the stock *D*, having the channel *b* between its sides, the blade *B*, having the slot *g* therein, the stud *H*, rigidly fixed in said stock and passing through said slot in blade *B*, the hinged stop *V*, adapted to swing across said channel *b* on one edge of said

stock, the washer *c*, loose on stud *H*, and the pointed screw-stem *I*, substantially as set forth. 10

ELI SMITH.
JAMES DUCKWORTH.
